UNITED STATES PATENT OFFICE.

ERNEST D. ANDERSON, OF LONG BEACH, NEW YORK, ASSIGNOR TO PASSAIC METAL WARE COMPANY, OF PASSAIC, NEW JERSEY, A CORPORATION OF NEW JERSEY.

CAN FORMING AND HEADING MACHINE.

1,315,000.

Specification of Letters Patent.

Patented Sept. 2, 1919.

Application filed April 29, 1916. Serial No. 94,497.

To all whom it may concern:

Be it known that I, ERNEST D. ANDERSON, a citizen of the United States, and resident of Long Beach, in the county of Nassau and 5 State of New York, have invented certain new and useful Improvements in Can Forming and Heading Machines, of which the following is a specification.

An object of my invention is to provide a 10 machine for automatically forming can bodies, applying heads upon such can bodies, and for seaming said heads upon the ends of the bodies in a continuous or successive manner. 15 Another object of my invention is to provide pneumatically controlled means for seaming heads or closures on can bodies, a further object being to cause such means to rotate around the can body and the head 20 applied thereto, for seaming the head and body together, in a continuous manner.

A further object of my invention is to provide means for automatically beading the end portions of the bodies opposite the head 25 applied thereon, and delivering the headed and beaded bodies from the machine.

Other objects of my invention, as well as novel details of improvement and combinations of parts, will be more fully hereinafter 30 set forth and then pointed out in the claims.

Reference is to be had to the accompanying drawings forming part hereof, wherein,

Figure 1 is a plan view of a machine embodying my invention, shown adapted for 35 applying heads to hollow bodies and seaming the heads thereon in successive steps, also having means to provide a bead adjacent to the end of the hollow body opposite the head thereon;

40 Fig. 2 is an end view of the support 7 carried by the turret A;

Fig. 3 is a longitudinal sectional view of Fig. 2;

45 Fig. 4 is a sectional plan view of a can body support carried by turret B;

Fig. 5 is a longitudinal sectional view of Fig. 4;

Fig. 6 is a side elevation of the machine, parts being omitted;

50 Fig. 7 is an end view looking from the righthand side of Fig. 6;

Fig. 8 is a detail view, enlarged, and

partly in section, of can-body seam-pressing or bumping dies shown in Fig. 7;

Fig. 9 is a sectional detail view of said 55 dies in the closed position;

Fig. 10 is a section on the line 10, 10, in Fig. 9;

Fig. 11 is an end view of said dies opened;

Fig. 12 is a sectional view of the can body 60 beader;

Fig. 13 is an end view thereof;

Fig. 14 is an enlarged detail sectional view of the beading dies closed;

Fig. 15 is an enlarged longitudinal sec- 65 tional view on the line 15, 15, in Fig. 1, through one of the rotary can head seamers;

Fig. 16 is an end view of Fig. 15, partly in section, substantially on the line 16, 16, in Fig. 15; 70

Fig. 17 is an enlarged detail sectional view illustrating packing between the spindle 55 and the rotary heads;

Fig. 18 is a cross section on the line 18, 18, in Fig. 15; 75

Fig. 19 is an edge view of seaming spindle or die 55;

Fig. 19^a is a sectional view on line 19^a, 19^a, Fig. 15;

Fig. 20 is an enlarged sectional view of 80 turret A assembled;

Fig. 21 is a plan view of the slide-carrying plate of turret A;

Fig. 22 is a plan view of plates 92 and 94 85 assembled of Fig. 20;

Fig. 23 is an enlarged sectional view, substantially on the line 23, 23, of Fig. 22, showing parts assembled;

Figs. 24 and 25 are details of block 93 and 90 head 95 of Figs. 20, 22 and 23;

Fig. 26 is a detail plan view of a Geneva movement adapted for operating the turrets;

Fig. 27 is a plan view illustrating the cam and mechanism for operating the slide-actuating cam for turret A; 95

Fig. 27^a is a detail of pin and slot connection;

Fig. 28 is a plan view of a slide-plate and cam plate therefor, for turret B;

Figs. 29 and 30 are detail views illustrating 100 operations of slides of Fig. 28;

Fig. 31 is a sectional view illustrating means for applying heads to can bodies, looking from the bottom of Fig. 1;

Fig. 32 is a side elevation of part of Fig. 31, being an enlargement of corresponding parts shown in Fig. 6;

Fig. 33 is a sectional plan view on line 5 33, 33, in Fig. 31;

Fig. 34 is a sectional detail of a can body and head applied thereto ready for seaming;

Fig. 34^a illustrates the head seamed on a can body;

10 Fig. 35 is an elevation illustrating a portion of a can-body-forming machine and means for feeding can bodies therefrom to my improved can heading machine;

15 Fig. 35^a is a detail view hereinafter referred to;

Fig. 36 is a plan view of a portion of the body-feeding device of Figs. 1 and 35;

Fig. 37 is a plan view of a portion of the body-feeding device omitted from Fig. 36;

20 Figs. 38 and 39 are sectional detail views, enlarged, of feeding and back-stop pawls of Figs. 1, 35, 36 and 37;

Fig. 40 is a section on the line 40, 40, in Fig. 36; Fig. 41 is a section on the line 41, 41, of Fig. 36; Fig. 42 is a section on the line 42, 42, in Fig. 36; Fig. 43 is a transverse section illustrating means for folding can bodies and pressing their seams; Fig. 44 is an enlarged detail section through 30 the can body former, and Fig. 45 is a perspective view of a blank for a can body.

Similar numerals and letters of reference indicate corresponding parts in the several views.

35 In the accompanying drawings the numeral 1 indicates a suitable frame adapted to support mechanism hereinafter explained. In the example illustrated, the frame 1 is equipped with a rotative device which I term, generally, a turret indicated at A, and with a substantially similar turret B, said turrets being suitably spaced apart. The turret A is provided with receivers for can bodies, that are adapted to successively receive can bodies from a can-body forming machine, or from any other desired source of supply, and while retaining the bodies thereon to present the bodies in different positions for different operations, such as for 40 straightening the bodies, applying heads thereto, seaming the heads on the bodies, and delivering the headed bodies from said receivers. Where the can bodies are to be beaded adjacent to their ends opposite the heads, the turret B is utilized, and as illustrated, is provided with means for taking the headed can-bodies from turret A and presenting them to devices for performing certain operations thereon, such as for forming the beads adjacent to the open ends of the can bodies, pressing the longitudinal seams of the bodies at the beads, and discharging the headed and beaded bodies. Referring now more particularly to the 45 ret A, and the devices co-operative there-

with for applying and seaming heads on the can bodies, it will be understood that the turret comprises various co-operative parts which may be described as follows: A vertically disposed shaft 2 is suitably journaled in bearings in the bed plate of frame 1, and said shaft is shown provided with a bushing or the like 3, shown resting upon frame 1 and secured thereto (Figs. 6 and 20) upon which bushing rests a turret plate 4 centrally disposed upon said shaft and suitably secured thereto, as by a key. Turret plate 4 is provided with a suitable number of radially disposed grooves or channels 5 (Figs. 20 and 21), in which slides 6 are disposed so as to slide radially. The slides 6 are provided with receivers 7 for can-bodies b, which receivers are shown provided with longitudinal grooves at 8 to receive the can-body seams, and at 9 the receivers are provided with can-body retainers, adapted to enter the bodies to retain them on the receivers 7 (Fig. 3). The retainers 9 are shown loosely mounted on the receivers 7 and held in place by pins 10 entering slots 11 in said receivers, springs 12 between receivers 7 and retainers 9 serving normally to press the latter outwardly. The outer ends of the receivers 7 and of the retainers 9 are shown beveled or tapered 95 for ready entrance into can bodies. The receivers 7 have abutments or stops at 13 against which the ends of the can bodies must abut for centering the bodies on the receivers and resisting end thrust of the 100 bodies. While the receivers may be formed directly on the ends of the slides 6, said receivers are preferably made separate therefrom to fit upon projections 6^a at the outer ends of the slides, clamping means, such as 105 screws 14, (Figs. 2, 3) serving to securely hold the receivers 7 on the slides. The outer ends of the receivers 7 are shown provided with recesses 15. A plate 16 secured upon plate 4, retains the slides 6 properly 110 in the grooves or channels 5, (Fig. 20). Plate 16 is retained on plate 4 by means of screws. Plates 4 and 16 are comprised in the turret, and the latter is held on shaft 2 by nut 17 receiving threads upon the end 115 of shaft 2 and bearing against an interposed washer or the like 18 (Fig. 20).

The slide-carrying plate 4 is to be rotated step by step, and each time said plate stops a can body may be placed upon one 120 of the receivers 7. I have illustrated means to automatically feed can bodies to the appropriate body-receiver 7, the discharge end of said delivery means being indicated at 19 in Fig. 1. The means illustrated for delivering can-bodies to receivers 7 will be more fully hereinafter described.

Any suitable means may be provided for rotating the slide-carrying plate 4 step by step. For such purpose I have illustrated 130

a Geneva movement comprising an escapement wheel or plate 20 having radial grooves 21 corresponding in position to the slides 6, and secured upon shaft 2 (Figs. 6 and 26). 5 An arm 22 having a projection or roller at 23 to enter grooves 21 rotates escapement wheel 20 in an ordinary manner. Arm 22 is secured upon a shaft 24 carried in suitable bearings on frame 1, and shown provided 10 with a bevel gear 25 meshing with a bevel gear 26 on a drive shaft 27 journaled in suitable bearings on frame 1, (Fig. 6). Shaft 26 may be driven in any suitable manner, such as by a sprocket wheel 28 secured thereon, receiving a chain 28^a from any suitable source of power, such as from the can-body forming machine as herein-after explained. Each time wheel 20 is moved a step a can body receiver 7 will be 15 brought to rest in position to receive a can body from the delivering part 19.

In order to properly seat can bodies on receivers 7, and to straighten the edges of the can bodies with respect to their seams, I 20 preferably cause the can bodies to be brought at their first stopping point opposite an abutment 30 secured on frame 1, and having a suitable surface to receive the outer ends of the can bodies, (Fig. 1). The abutment 25 30 is preferably provided with a pin or projection 31 to enter the recesses 15 of receiver 7 to cause the latter to be properly centered when the receivers with the can bodies are successively pushed toward said abutment 35 (Fig. 1), as will be presently explained. At the next step, each can body is brought to rest in position with respect to means for applying heads *a* upon the bodies *b* (Figs. 1, 31, 32 and 33). The heads *a* are illustrated of the class having the depressed portion *a'* adapted to enter the can body *b* at its end, while the flange *a''* of the head projects outwardly to be seamed over the edge of the can body (Figs. 31, 34 and 34^a). In 40 the example illustrated a suitable magazine for heads *a* is illustrated at 32, carried by a standard 1^a on frame 1, adapted to receive a suitable stack of heads *a* (Figs. 1, 6 and 31), fingers at 33, pivotally supported upon 45 standard 1^a, engaging the lowermost head of the stack, springs 34 co-operating with said fingers and the magazine serving normally to retain the fingers closed with respect to the heads for supporting the latter. 50 Beneath the magazine 32 I have shown means for taking off the lowermost head *a* of the stack and presenting it opposite the can body on the opposing or adjacent body receiver 7, the arrangement shown for such 55 purpose being as follows: A rocking arm 35 is shown carried by a shaft 36 journaled in bearings upon standard 1^a (Figs. 31 and 33), and said arm 35 is shown provided with a hollow or recessed portion which receives 60 a polygonal block 37 through which a shaft 65

36 passes. A spring 38 interposed between said block and the outer end of arm 35 normally tends to move said arm toward the left in Fig. 31. At the outer end of said arm is pivotally supported a head 39 recessed at its outer end and adapted to enter the recess of the can heads *a*. Head 39 is shown pivotally supported upon a shaft or pin 40 carried by arm 35, a spring 41, interposed between arm 35 and head 39, normally tending 70 to push said head forwardly to a tilted position to resiliently engage can heads, and enter them angularly. A tube *d* leads from a source of air suction or exhaust to a port 39^a in head 39. On opposite sides of arm 80 35 are arms 42 secured upon shaft 36 and having suitably curved cam-like forward edges 42^a adapted to coact with shaft 40, or with rollers 43 thereon (Fig. 33), to cause required movements of arm 35 and head 39. 85 Shaft 36 is to be rocked at a suitable time, for which purpose I have shown said shaft provided with a toothed segment 44 in mesh with a rack 45, suitably guided upon standard 1^a and pivotally connected by a link 46 90 with a rock arm 47, pivotally supported by frame 1 and connected by a link 48 with a crank 49 carried by shaft 27 (Fig. 6). When arm 35 is in the position for application of a head *a* to a can body said arm will bear 95 against a stop 50 on standard 1^a, as in full lines in Fig. 31, and when said arm is brought to the can-head receiving position the arm will rest against a stop 51 on said standard, as indicated in dotted lines in Fig. 100 31. When arm 35 is to receive a can head, the racks will operate to cause said arm to be rotated to the position shown in Fig. 31 with its head 39 beneath the magazine, the engagement of shaft 40 with the cam-like ends 105 of arms 42 causing arm 35 to be carried with arms 42, and when arm 35 rests against stop 51 head 39 will be in proper position beneath the can bodies. A further movement of arms 42 to the left in Fig. 31 will cause arm 35 110 to be pushed upwardly to bring its head 39 in engagement with the lowermost can head *a* in the stack, by reason of the cam surface 42^a in coaction with shaft 40, and thereupon suction through tube *d* will be caused by any 115 suitable means to pneumatically retain such can head on head or plate 39. The racks will then so operate that arms 42 will return to the right in Fig. 31, and spring 38 will cause arm 35 to descend and carry with it said 120 lowermost head *a*, dragging it from between the spring acting fingers 33, which will thereupon snap under the lowermost head *a* of the stack to retain the stack in the magazine, while permitting the can-head 125 upon plate 39 to move away with arm 35. Said arm with arms 42 will continue to move to the right in Fig. 31 until arm 35 rests against stop 50, bringing head *a* in position to receive a can body *b*. When the parts 130

are in such position (Fig. 31) the now opposing can receiver 7 will be moved with can body 6 toward the head α that is upon head 39, and when said head has been entered in the can body, (substantially as shown in Fig. 34), and retained by friction, suction through tube d will be cut off, and the can body with the head applied will be withdrawn, the movement of the can body 10 toward and from head 39 being effected as presently described. The foregoing operations occur with each head to be applied upon a can body in succession.

After a head is applied upon a can body 15 the turret A will rotate to carry the headed can to the position to have the flange α^2 seamed on the body. In the example illustrated in the accompanying drawings, the arrangement is such that the turret will 20 make two stops from the position where the head is inserted in the can body to the position where the flange α^2 is seamed on the can body, as illustrated in Fig. 1. The devices for seaming heads on can bodies are 25 shown in detail in Figs. 15 to 19^a, and comprise means to bear on and rotate around the flanges of the heads, and to be pressed thereon under pneumatic pressure in accordance with the shape of the can and its head. A 30 spindle 55 is supported on a bracket or the like 56 secured on frame 1, and is provided with a suitable chuck 57, substantially conforming to the shape of the can head α and adapted to enter the recess thereof. The 35 chuck 57 is preferably detachably connected with spindle 55, as by means of a screw 58 (Fig. 19). At 59 are rollers suitably spaced apart around the chuck 57 and pivotally supported upon arms 60 to move relatively to 40 ward and from chuck 57. The arms 60 are pivotally supported at 60^a upon a rotative head 61, that is mounted to rotate upon spindle 55, and which may be driven by a belt from a suitable source of power, or in any 45 other suitable manner. The arms 60 and thereby the rollers 59 are maintained, during operation, pressed toward the can heads presented thereto upon the corresponding receiver 7, and for such purpose I have shown 50 head 61 provided with cylinders 62 in which are located pistons 63 operatively connected with the corresponding arms 60. For such purpose I have shown arms 60 provided with projections 60^b receiving pins 64 carried by 55 the respective pistons 63. The arms 60 also carry suitable rollers 65 adapted to bear upon a master form 66, that is slidable upon spindle 55, and around which master form the rollers 65 roll when head 61 rotates. 60 Means are provided to supply fluid pressure in the cylinders during the operation of the seaming on the can heads to cause the rollers 59 to press on the flanges of the can heads. I have shown the head 61 provided with an 65 annular channel 67 communicating with the

respective cylinders 62, said channel being in communication with one end of a passage 68 carried by head 61 for supplying fluid under pressure to the channel, such as compressed air. The opposite end of passage 70 68 communicates with a chamber 69 shown located between the hub of rotative member 61 and spindle 55, suitable packing at 70 in said hub serving to prevent leakage of air in different positions of rotary head 61. 75 The cup-packing 70, may, as illustrated in Fig. 17, be in the form of a cup-like ring-packing held in place by screws 71. The packing may be retained in place by a suitable nut or gland 71^a (Fig. 15). The channel 67 may be provided between the periphery of head 61 through which the cylinders open, and a shell or ring 67^a surrounding and fitting tightly thereon, and held in place by a nut or ring 67^b on head 61, (Figs. 15 80 and 16). By removing shell or ring 67^a access may be had to the cylinders and pistons. The chamber 69 may be supplied with compressed air through a channel 72 in spindle 55, the inner end or port 73 of said 90 channel communicating with chamber 69, while the outer end of the channel is connected by tubing 74 with a source of compressed air supply. The passage 75 in spindle 55 may supply lubricating oil to the 95 bearing of rotative member 61, as through a tube 76 from a suitable source of supply. The master form 66 is preferably shaped substantially to conform to the shape of the can body and its head, the shape illustrated 100 in the accompanying drawings being substantially oval. By means of rods 77 slideable in bores in spindle 55, and suitably connected with master form 66, said master form may be slid back and forth along spindle 55 105 by any suitable means, suitably timed to permit rollers 55 to gradually approach the can head as the flange thereof is reduced in diameter by the pressure of said rollers thereon. I have illustrated means in Fig. 1 for 110 causing such movement of master 66 as will be presently described. The arrangement is such that when a can body with its head applied (Fig. 34) is presented to the chuck 57 it is pushed thereon a suitable distance, 115 while the master 66 is substantially in the position shown in Fig. 15, holding rollers 59 retracted. As the head 61 with the pistons and rollers continually rotate, the master 66 will be gradually pulled outwardly from 120 under the rollers 65, thereby permitting the air pressure against the pistons to force the rollers 59 against the flange of the can body for rolling the same down for seaming the flange, the continued outward movement of 125 master 66 permitting the rollers 59 to act upon the flange α^2 to the desired extent. When the flange α^2 has been seamed as desired the master 66 will be moved reversely 130 to spread rollers 59 from the can head to

permit proper removal of the latter and replacement of another in seaming position, and so on, the air pressure in the cylinders being applied and removed or reduced as desired.

It is desired to maintain a substantially equal pressure on rollers 59 in all positions of their acting upon the flange of the head α . For this purpose all of the cylinders 62 communicate with the single channel 67, whereby the pressure in the cylinders will be equalized, while the pistons are caused to reciprocate by contact with the oval or other shaped flange of the can head during rotation of member 61. Suitable means, such as an automatically operating valve, may be provided for causing pressure in channel 67 to be started just before the master form 66 is pulled to the right in Fig. 15, and to be relieved just before master form 66 is pushed to the left in Fig. 15, to then relieve the pressure of rollers 65 on said master, so that when the master form is pushed to the left to cause withdrawal of rollers 59 to the opened or spread position, the work of pushing the pistons outwardly against air pressure will be reduced. The desired pressure may be admitted to channel 67 just after a can body with its head α applied is presented between rollers 59, and such pressure may be continued until said rollers have acted sufficiently or as desired upon the flange of said head. In Fig. 1 the tube 74, which may communicate with the corresponding channel 72 of both rotary seaming heads, connects with a suitable air-controlling valve 78 receiving compressed air through pipe 79 from a suitable source. A cam 80 (Figs. 1 and 6) on shaft 27 may operate an arm 81 for controlling valve 78 at the required time to admit air pressure to and relieve it from channels 67. Valve 78 may have a vent to relieve the pressure in channels 67. Valve 78 may be any well-known quick-acting valve such as ordinarily used for air or steam.

While the desired action of rollers 59 upon a can-head flange may be utilized with a single rotary head 61 for seaming, it is preferable, in some instances, to utilize two of such sets of devices, as illustrated in Fig. 1, the first set (at the left in Fig. 1) for partially turning or seaming the flange and the second set for completing such seaming. The two rotary heads may be substantially the same as described with respect to Figs. 15 to 19^a, but will be so set with relation to each other and to turret A that the rotary head 61 at the right in Fig. 1, will be in position to receive a partially seamed can body and head on the next step of turret A after a body having a partially seamed head has been withdrawn from the left hand rotary head 61 in said figure.

65 When the partially seamed flange of the

can body has been presented in right hand rotary head 61, the pressure will be admitted in its channel 67 for causing its pistons and rollers 59 to act with the required pressure for finally seaming the flange α^2 , the corresponding master 66 being operated in a manner before described. The masters 66 may be automatically actuated, and said masters of both rotary heads may be operated together by the following means: Rods 77 of the left hand head 61 are secured to a block 82 (Fig. 1) that is connected with a bell crank lever 83 pivoted upon bracket 56; a rod 84 pivotally connects lever 83 with a corresponding bell crank lever 85, pivotally supported upon bracket 56 with respect to the right hand rotary head 61, arm 86 connected with lever 85 being connected with a block 87 that is connected to the rods 77 of the right hand head 61. A rod 88 is pivotally connected at one end with lever 85 and at the other end said rod is provided with a guide yoke 88^a having a pin 89 coaxing with a cam 90 secured upon shaft 24^a journaled in bearings in frame 1 (Figs. 1 and 6). As cam 90 is rotated, the rods 77 of the respective rotary heads 61 will be reciprocated at the proper time for moving the respective master forms 66 back and forth with respect to the corresponding rollers 65 of the respective pistons. After the seaming has been finished upon the can head, by the devices of the right hand rotary head 61 (Fig. 1), the can body is withdrawn from said head and at the next step of turret A said can body is brought to a position indicated at α in Fig. 1, ready to be discharged or removed from the corresponding receiver 7.

While any suitable means may be provided for rotating turret A step by step, and for causing the can body receivers 7 to be projected outwardly and drawn in with can bodies thereon, I have illustrated means for such purpose as follows: Since turret A is illustrated as provided with eight can body receivers 7, the plate 4 is shown provided with eight grooves or recesses 5 receiving the corresponding slides 6 (Fig. 21), and the Geneva wheel 20 is shown provided with eight correspondingly disposed grooves 21 (Fig. 26), whereby the turret A will be given eight steps for each complete rotation thereof. Since, in the example illustrated, there are six points at which operations occur with respect to a can body, such as the application of a body to a receiver 7, the straightening of the seam of the can body, at 30, the application of the head to the can body adjacent to the magazine 32, the seaming of the flange of the can body head at the two rotary heads 61, and the delivery point for the headed can bodies at the point α , I provide means to cause the receivers 7 to be moved outwardly and inwardly for each of such six points, the other

two points at which the receivers 7 are brought by the rotation of Geneva wheel 20 not requiring relative movement of the receivers, such points being indicated at y and y^2 in Fig. 1. To cause the receivers 7 to be projected and withdrawn at the proper points I provide devices as follows: Beneath plate 4 and concentric with rotatively guided shaft 2 is a plate 92 (Figs. 6, 20, 22 and 23). Plate 92 is shown provided with six appropriately located radially disposed slots or grooves 92^a, shown opening through the periphery of said plate, adapted to slidably receive blocks 93. Said blocks are shown provided with flanges 93^a, on opposite sides, bearing against the bottom of plate 92, which blocks slidably rest upon a cam plate 94 that is rotatively supported beneath plate 92 and guided around shaft 2, (Figs. 6, 20, 22, and 23). Plate 92 is shown provided with an annular groove or raceway 92^b (Fig. 22) which communicates with the slots or grooves 92^a. The blocks 93 are provided with transverse grooves 93^b, which open through the sides of said blocks, which grooves 93^b are adapted to coincide with the annular groove or raceway 92^b of plate 92, in certain positions of blocks 93 (Fig. 22). Heads 95 are adapted to slide in groove 92^b, being shown provided with curved surfaces for such purpose (Figs. 22 and 25), which heads are adapted to enter the grooves 93^b of blocks 93 to be moved therewith radially respecting plates 92 and 94 (Figs. 20, 22, 23, 24). Heads 95 receive pins 96, shown adapted to fit in openings 95^a of said heads, and also fitted in openings in slides 6, said pins being adapted to slide in radially disposed slots 4^b in plate 4 (Figs. 20, 21 and 23). Since, in the example illustrated, there are eight slides 6, there will be a corresponding pin 96 and head 95 for each slide 6, and since there are six points at which operations occur with respect to the can bodies of turret A, the six grooves 92^a and six blocks 93 in such grooves will suffice, although all of the eight heads 95 may operate in succession in the grooves of corresponding blocks 93. When a head 95 is in the groove of a block 93, the latter is to be moved radially, and a corresponding slide 6 with its can body receiver 7 will be correspondingly moved because of the interposed pin 96. Any suitable means may be provided for reciprocating blocks 93 in grooves 92^a of plate 92 at the proper times. For such purpose I have shown plate 94 provided with cam grooves 94^a positioned with respect to grooves or slots 92^a of plate 92 and adapted to receive pins 97 that project from blocks 93 (Figs. 22 and 23). By preference, rollers 98 are carried by pins 97 for engagement with the cam grooves 94^a. Pins 97 may be retained in position by nuts 99 seated in recesses 93^c in blocks 93, (Figs. 20 and 24).

The arrangement described is such that when cam plate 94 is rocked or oscillated, its grooves 94^a, by coaction with pins 97, will cause blocks 93 to be reciprocated. When plate 4 is brought to rest a head 95, corresponding to a slide 6, is presented in the groove 93^b of one of the blocks 93, and then cam plate 94 is given a to and fro movement, whereupon its cam grooves 94^a cause blocks 93 to move outwardly and then inwardly, carrying slides 6 and receivers 7 therewith, terminating the stroke with heads 95 in register with groove 92^b of plate 92. On the next step of plate 4 the heads 95 pass through groove 92^b until certain of said heads rest in the grooves 93^b of the next adjacent blocks 93, whereupon cam plate 94 is again moved to and fro to cause certain slides 6 to be again moved outwardly and inwardly, and so on each step of plate 4 where slides 6 are to be given a to and fro movement. The foregoing pertains to six of the slides 6, whereas the heads 95 of two other slides, not then to be reciprocated, as with respect to the points y and y^2 (Fig. 1), will be in the appropriate parts of groove 92^b of plate 92, and so on. The means I have shown for oscillating plate 94 are as follows: At 100 is a cam secured upon shaft 24 above frame 1, (Figs. 6, 27 and 35), and adapted to coact with a pin or roller 101 carried by a rod or link 102, shown having a forked end 102^a guided by shaft 24, the opposite end of said rod or link being pivotally connected with plate 94, as by pin 103, which is shown adjustable in a slot 104 in plate 94 (Fig. 27). When heads 95 have been presented in grooves 93^b of blocks 93, and plate 4 has come to rest, cam 100 will, through link or rod 102, cause plate 94 to be rocked or reciprocated to and fro one stroke each way, whereby the cam slots 94^a will cause blocks 93 and slides 6 to be moved in and out, terminating the stroke with heads 95 in register with groove 92^b of plate 92.

If no further operations are desired to be performed upon the can bodies while they are carried by turret A, after the bodies have been headed and seamed, the can bodies may be removed. In the example illustrated in the accompanying drawings I have provided means for removing the headed can bodies from turret A and supporting them upon a second or companion turret B that is spaced a suitable distance from turret A upon frame 1. Turret B may be made substantially in the same manner as turret A and provided with a corresponding number of can body gripping or receiving devices indicated generally at 7^a, which may be removably attached upon the ends 6^a of slides 6, as by clamping screws 14^a in manner similar to that described with respect to slides 6. Turret B may have plates 4^a and 16^a receiving slides corresponding to 130

slides 6 of turret A, together with the plates 92^e and 94^e and interposed blocks 93^e and pins connecting said parts, in manner described with respect to turret A, for causing the gripping or receiving devices 7^a to be projected and retracted as turret B rotates step by step. A Geneva movement, having a cam wheel 20^a provided with slots 21^a and an arm 22^a having a pin or roller to 5 coact with said slots and carried by a shaft 24^a supported by frame 1 may be operated in timed relation to turret A through gearing 25^a, 26^a and shaft 27 for causing step by step rotation of turret B simultaneously 10 and coincidently with respect to turret A, (Fig. 6). In the example illustrated the can bodies having the heads seamed thereon, as hereinbefore described, are brought to rest successively upon a receiver 7 of turret 15 A, opposing a gripping or receiving device at 7^a of turret B, and at suitably spaced distances around turret B means are provided for beading the can bodies adjacent to their ends at b² (Fig. 14) opposite their 20 heads, at the position shown at z Fig. 1, and for "bumping" or pressing the seams at the beads b², as at the point z² (Fig. 1), and for delivering the can bodies from turret B as at the point z³ (Fig. 1). Since, as illustrated, 25 there are but four points of operation with regard to the can bodies respecting turret B, it will only be necessary to cause the gripping or receiving devices 7^a to be projected and retracted at each of such four 30 points. Hence, as shown in Fig. 28, plate 92^e is provided with four radial grooves 92^f (corresponding to the grooves 92^a, Fig. 22), and plate 94^e has four corresponding cam slots 94^f (corresponding to the cam slots 94^a 35 of plate 94 Fig. 22). Plate 4^a carrying the slides 6^a that support the grippers or receivers 7^a, will be provided with eight slots and slides in the manner illustrated and described with respect to Figs. 20 and 21, 40 and the pins 97^a from blocks 93^e will work in the cam slots 94^f similar to the corresponding parts described with respect to turret A. The blocks 93^e have transverse grooves 93^f adapted to receive blocks 95^e receiving pins 96^e (Figs. 28, 29, 30) from the corresponding slides 6^a, (in manner described with respect to similar parts in 45 Figs. 20 and 21). Plate 92^e has the annular groove 92^g communicating with the slots or grooves 92^f for the passage of the heads 95^e, (in manner similar to that before described 50 regarding turret A). Turret B is mounted upon a shaft 2^a connected with Geneva wheel 20^a in manner similar to the connection of shaft 2 with Geneva wheel 20 of turret A. Cam plate 94^e of turret B is to be rocked to and fro in unison with cam plate 94 of 55 turret A, for which purpose a rod 105 (Figs. 1, 6, 22 and 28) is pivotally connected to plate 94 at 106 and with plate 94^e at 107,

and by means of suitable pin and slot connection between said rod and said plates adjustment may be made for accurate movement of one plate by another. Such pin and slot connection may be similar to that shown 70 in Fig. 27^a. By the means described the single cam 100 may be utilized for oscillating plates 94 and 94^e in unison and to the same extent to assure that the respective slides 6 and their opposing receivers 7 and 7^a (Fig. 1) will all work together in proper timed relation.

The receivers 7^a of turret B are provided with means for gripping the headed ends of the can bodies and removing said bodies 80 from the receivers 7 of turret A and retaining said bodies for operations thereon and discharge thereof from receivers 7^a. As shown in Figs. 1, 4 and 5 the receivers 7^a are provided with gripping fingers 108 85 pivotally carried by shafts at 109 on opposite sides of the receiver adapted to grip the headed end of cans b therebetween. Springs 110 connect arms 111 respectively secured to shafts 109 for normally drawing the fingers 90 108 toward the can body. One of the shafts 109 of each receiver 7^a is provided with an arm 112 for causing discharge of the can bodies as hereinafter explained. The shafts 109 are connected by projections 113 with a 95 plunger 114 slidable in a bore in the corresponding receiver 7^a, and normally held retracted in line with the head of a can body when the latter is held between the fingers 108. When arm 112 has operated fingers 100 108 to release a can body the plunger 114 will be pushed forwardly to discharge a body from receiver 7^a. When a headed can body is brought to rest on a retracted receiver 7 at the point x (Fig. 1) a receiver 105 7^a will be retracted opposite said can body. When the plates 94 and 94^e are next rocked to cause the corresponding slides 6, 6^a, to move outwardly, the receiver 7 carrying the can body and the receiver 7^a opposed thereto 110 move toward each other, and the corresponding fingers 108 snap over the headed end of such can body and then when plates 94 and 94^e are again rocked reversely said receivers 7 and 7^a are moved apart and the can body, 115 then held by fingers 108, is withdrawn from receiver 7 and retained upon receiver 7^a. On the next rotary step of turret B in the direction of the arrow thereon (Fig. 1) said receiver is not projected outwardly, but on 120 the next step of turret B, said receiver, with the can body thereon, is projected outwardly by the appropriate cam slot 94^f to locate the open end of the can body in position to be beaded adjacent to said end, at the position z (Fig. 1). Devices for beading can bodies are shown in Figs. 1, 6, 7, 12, 13, and 14. At 115 is a head supported by a bracket 116, carried by frame 1, in position opposite a 125 can body when brought to rest by turret B. 130

Bracket 116 is shown adjustably supported upon frame 1, and which may be adjusted by screw 117 and retained in set position by screw 118 (Fig. 7). Head 115 is shown 5 provided with a recess 115^a (Fig. 12) within which a male die comprising a plurality of expansible sections 119 is located, the sections being suitably shaped to enter the can body. Springs 120 serve normally to press 10 said die sections inwardly, and a mandrel 121 is slidably fitted within said die sections, the outer surface of the mandrel and the inner surface of the die sections being shown tapering (Fig. 12) whereby, when the mandrel is pushed to the left in said figure, the die sections will be expanded within can body b. Said mandrel is shown carried by 15 a rod 122 slidably in a bearing on bracket 116. At 123 is a lever or arm shown pivotally supported at 124 on bracket 116, and operatively connected by pin and slot connection 122^a, 123^a with rod 122 (Figs. 7 and 12). A spring 125 connecting lever 123 with frame 1 normally tends to retract mandrel 20 121 from dies 119. Lever 123 is shown connected with a rod or link 126 which is adapted to be operated by cam 80 on shaft 27 (Fig. 7), the rod or link 126 having a pin or roller 128 to coact with said cam and having a forked end 126^a guided by shaft 27. Surrounding die 119 is a female die comprising slides or sections 130 which are guided in suitable ways in head 115 and normally pressed from die 119 by springs 25 131 interposed between head 115 and die sections 130. An apertured plate 132 secured on head 115 serves to retain die sections 130 in slidable position on the said head. At 133 are cam-like projections carried by a head or disk 134 supported by rod 122 (Figs. 1 and 12). The cam-like projections 133 are suitably inclined at 133^a to coact with correspondingly inclined surfaces 130^a on die sections 130 for causing said 30 sections to approach the can body b. The outer ends of projections 133 are shown guided in openings in plate 132 (Fig. 12). The arrangement is such that when a can body b is presented in front of head 115, the die 119 will be collapsed and the die 130 will be expanded, and thereupon when plate 35 94^a is rocked to cause the corresponding receiver 7^a to be projected outwardly, the can body will be presented between said dies, as illustrated in Fig. 12, and thereupon lever 23 will be rocked to cause mandrel 121 and projections 133 to slide within the dies to cause the die 119 to expand and the die 130 to collapse, whereupon the can body will be 40 beaded by said dies, as indicated at b^a in Fig. 14. Rod 122 will thereupon be retracted to cause the dies to move away from the can body, and the receiver will be retracted to withdraw the beaded can body from the 45 dies.

Upon the next step of turret B the beaded can body will not be projected, but after the turret has come to rest on the following step at the point z^a (Fig. 1), said can body will be projected outwardly in position to 50 have its seam b^a at the bead b^a "bumped" or pressed (Figs. 9 and 10). I have illustrated normally spaced opposing dies at 135, 136 having respectively a groove 135^a and a projection 136^a (Figs. 7-11), said 55 groove and projection being adapted to receive the beads of the can bodies. The die 135 is shown supported by a head 137, screws 138 carried by said head and bearing against said die serving to retain the die in adjusted position on said head with respect to die 136. The head 137 has an extension 137^a supported by a cross head or tie-bar 139 carried by posts 140 secured on the base of frame 1, and suitably spaced 60 apart. A nut 141 on extension 137^a secures the latter and head 137 on cross head 139. A block 142 slidably receives posts 140. Die 136 is carried by a rod 143 (Fig. 7) that is adjustably secured to a block 142 65 slidably on posts 140. Said block is pivotally connected at 144 with a rod having a yoke 145 operatively connected with an eccentric 146 secured on shaft 27. The arrangement is such that when turret B is 70 brought to rest, with a headed and beaded can body, at the point z^a (Fig. 1), with the seam b^a of the body in position opposing the space between the then separated dies 135, 136, plate 92^a will be rocked to cause 75 the can body to be projected with its seam between said dies and its bead b^a opposing the groove 135^a, and projection 136^a of said dies, and thereupon eccentric 146 will cause die 136 to operate to "bump" or press the 80 seam between the said dies to smooth and reset the seam where it has been pressed by the beading dies. The die 136 will then move back to release said can body and the plate 92^a will rock to withdraw the can body 85 from said dies. 90

Upon the next step of turret B the beaded and bumped can body will not be projected, and at the next step of said turret, at the point z^a (Fig. 1), said can body will be 95 brought to rest over a support or conveyer 150 for release thereon. I have shown a stop 151 having an inclined or cam-like edge (Figs. 1 and 7) located in the path of arms 112, or of a projection or roller 112^a on each 100 arm, whereby when plate 92^a is first rocked after turret B stops with a can body at z^a, the corresponding receiver 7^a with such body will be moved outwardly and its arm 112, by engagement with stop 151, will be 105 rocked to cause spreading of fingers 108 and the advancing of plunger 114 for releasing and discharging the headed, beaded and bumped can body from its receiver 7^a to 110 fall upon conveyer 150. Upon the return 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 stroke of said receiver 7^a the arm 112 will be released from stop 152 to permit fingers 108 to be restored to their normal position ready to receive a can body between them.

- 5 At a stop of turret B with a receiver 7^a, between the point of discharge of the can body z^a and the point of reception of the can body at z , such receiver need not be projected outwardly, but it will be projected 10 outwardly after the termination of the next step of the turret B when such receiver reaches the point z to receive a can body, as before explained.

The can bodies to be headed may be fed 15 to the receivers 7 in any desired manner. I have illustrated means for feeding the can bodies to said receivers from a body forming mechanism successively in timed relation to the movements of turret A.

- 20 A portion of said body forming mechanism is indicated in Fig. 35, and a suitable track or guideway, indicated generally at 156, extends from the body forming devices to the delivery point 19 opposing the 25 can body receiving position of receivers 7 of turret A. The operating shaft 157 of the body forming machine (Fig. 35) is shown provided with a sprocket wheel 158 receiving chain 28^a from sprocket wheel 28 30 of frame 1. Either of said shafts may be the driving shaft rotated in any suitable manner, and the relation of the gearing between shafts 157 and 27 is such that the can bodies will be moved along track 156 35 in timed relation to the stopping of turret A and the outward movement of a receiver 7 thereof to receive a can body as fed from the delivery end 19 of said track whereby when said receiver having a can body thereon is retracted it may be moved away with 40 turret A, to the left in Fig. 1.

The blanks b^4 for the can bodies (Fig. 36) may be formed and seamed around the former 159 of the body forming devices by any 45 suitable or wellknown means, the track 156 being fitted adjacent to such former to receive the can bodies therefrom. In Fig. 43 I have shown arms 200 pivotally supported at 201 and connected by linkage at 202, 203 50 with a cam 204 on shaft 157 whereby said arms will be caused to fold the blank b^4 around former 159 to unlock the edges of the blank for the seam. Said former is shown provided with a recess 159^a to receive 55 the seam of the can body. The seam may be closed by a presser 205 shown pivotally supported at 206 and connected with a rod 207 having a pin 208 to coat with a cam 209 on a shaft 157. Spring 210 serves to retract presser 205 from former 159 and retain pin 208 coactive with cam 209. The timing of said parts is such that each time a blank b^4 is placed beneath former 159 the 60 arms 200 will fold the blank around the former and lock its edges and the presser 65

205 will close the seam, whereupon the body b will be fed from the former. The end 19 of track 156 rests upon a roller 160 that is journaled in a bracket 161 on frame 1 (Figs. 1, 35, 36 and 40), so that when hollow can 70 bodies surrounding said track are slid along the same the under portions of said bodies may slide on roller 160, and raise the track slightly as necessary, as said bodies are fed between the track and roller. The track is 75 shown comprising spaced angle bars 162 adapted to receive the hollow can bodies slideable thereon, the lower edges of the angle bars 162 being suitably shaped to receive roller 160, filling pieces at 163 (Fig. 40) being provided at said bars, the edges of which filling pieces are suitably curved to correspond to the roller 160. To feed the hollow bodies along the track a reciprocative member 164 is provided, extending longitudinally with respect to the track and former mandrel 159, a portion of which member 164 is guided in a groove 159^a on mandrel 159 (Fig. 41), and a portion of which member 164 is guided in the space between the 80 upper angle bars 162, interposed spaced blocks 165 retaining the upper and lower pairs of members 162 spaced apart. A portion 164^a of member 164 is supported to reciprocate in a suitable guide 166 of the body 85 forming machine (Fig. 37) which portion is shown pivotally connected by a link 167 with an arm 168 that is suitably supported at 169 (Fig. 35^a), a portion 168^a of which arm is pivotally connected at 170 with a forked 90 rod 171 guided by shaft 155 having grooved cam 172 (Fig. 35) receiving a projection 171^a of rod 171. By the connection of the 95 gearing between shafts 155, 157 and 27, the member 164 is timed to reciprocate in accordance with the steps of turret A to deliver a can body from track 156 to a receiver 100 7 of said turret each time a receiver is stopped in front of said track. Member 164 is provided with any suitable number of 105 dogs or fingers 173, which are pivotally supported at 174 in recesses 175 in member 164 (Fig. 38). Said dogs are properly spaced apart so that the upper corners 173^a of said dogs may engage the rear edges of the bodies 110 b that are upon track 156, (Fig. 38). At 176 are springs shown secured in recesses 175 by screws, which springs act upon dogs 173 to normally retain them with their edges 173^a projected above member 164, to engage 115 bodies b on the forward or body feeding strokes of said member, and to permit said dogs to tilt to slide under said bodies when member 164 is retracted. Back stop dogs 177 are shown spaced apart and pivotally 120 supported at 178 upon the outer side of an upper angle bar 162 of the track, in position to engage the rear edges of hollow bodies b on the track to retain the latter 125 from being dragged back along the track 130

after being fed forwardly thereon by the feeding dogs 173 (Figs. 1, 35, 36 and 39). Suitable springs 179 are attached to said angle bar, as at 180, one end of each of said 5 springs bearing against a stop 181 on the track and the opposite end against the corresponding dog 177, whereby said dogs are normally maintained with the upper corners 177^a in the path of the hollow bodies *b* 10 on the track. The dogs 177 may tilt as the hollow bodies slide over them on the track, but after such bodies pass beyond corners 177^a of said dogs the latter will return to normal to resist rearward movement of said 15 bodies. It will be understood that the length of the track may be such as to permit several can bodies *b* to slide thereon at one time, and that the number of dogs 173 and 177 will be in accordance with the length of the track 20 and the length of the bodies *b* to be fed thereon, and spaced apart accordingly.

The complete operation of the machine may be described as follows: When the machine is started the can bodies will be formed 25 in the body forming devices and fed along track 156 step by step in correspondence with the step by step rotation of turrets A and B, the seaming heads 61 also being rotated. Assuming, first, that no can bodies 30 are on the receivers of the turrets, then when a can body has about been presented at the delivery end 19 of the track, a receiver 7 will be opposed to such can body (Fig. 35), and thereupon further movement of various 35 parts will cause such can body to be projected from the end of track 156, and said receiver will be projected toward the track, and will enter the body *b* as indicated in dotted lines in said figure. Thereupon plate 40 40 will operate to cause the receiver to be withdrawn to carry the body *b* thereon away from the track, and when the receiver has assumed the normal inward position, with the block 95 and its slide 93 in register with 45 groove 92^b of plate 92, the turret will be rotated a step by the corresponding Geneva movement. When the turret comes to rest said block will be in register with the corresponding radial groove 92^a of plate 92. 50 Plate 94 will again operate, whereby a slot 94^a thereof will cause said slide to project outwardly, whereupon said block will carry said receiver 7 outwardly with the can body thereon into engagement with abutment 30, 55 for straightening the seam of such body. When such receiver is thus moved outwardly, the receiver that is then in front of the track 156 will also be moved outwardly to receive a body *b* from said track 60 in the manner before described. Plate 94 will now operate to withdraw both receivers, and thereupon the turret will be given another step, causing the first mentioned can body to be brought opposite the can head 65 applying devices, and the second named can

body to be brought opposite abutment 30, and another receiver to be brought opposite the track, the corresponding blocks and slides operating in manner before described. Plate 94 will be given another movement, 70 whereupon said receivers will be moved outwardly, the head applying devices then operating, in manner before explained, to apply a head *a* upon the first named can body, the seam of the second named can 75 body meanwhile being straightened at the abutment 30, and the third named receiver receiving another body from track 156. The receivers will then be retracted by movement of plate 94, and upon the next step 80 of the turret the body *b* now having a head applied will stop at the point *y*, the second named body will be brought to the can head receiving position, the third named body will be brought opposite abutment 30, and a 85 fourth receiver 7 will be presented opposite the track. Upon the next movement of plate 94 all of said receivers will be projected, except the one at the point *y*, for corresponding operations upon the second and 90 third named bodies and for the application of a body to the fourth named receiver. After said receivers have been withdrawn on the next movement of plate 94 the turrets will be given another step, and the first 95 named can body having the head applied will be brought opposite the first rotary seamer head 61, with the other can bodies in their respective positions as described. When plate 94 next operates all of said receivers will be projected, except the one at *y*, and the first named body with its head applied will be pushed toward said rotary head 61 with the head of the can body in position between the rollers 59 of the rotary 100 head. Thereupon valve 78 will operate to admit pressure in the cylinders of rotary head 61 to cause rollers 59 to bear upon the flange of the can head, for partially seaming the same, the corresponding master form 105 66 being moved to the right in Fig. 15, to permit said rollers to bear with pressure upon the flange of the can head during rotation of head 61. When such seaming operation has been finished, valve 78 will operate 110 to cut off pressure from the cylinders of rotary head 61, and relieve pressure by opening the bypass or vent, and thereupon master form 66 will be moved back to withdraw rollers 59 from the can head flange, the plate 94 being also operated at the proper time to cause retraction of the receivers 7, whereupon such partially seamed can head is withdrawn from rotary head 61 115 and bodies on other receivers are likewise withdrawn from their respective positions of operation. After the next step of turret A the receivers 7 will be projected, except at *y*, causing the first named receiver to push the partially seamed head *a* into position 120 125 130

between the rollers 59 of the rotary head 61 at the right in Fig. 1, and the adjacent unseamed can head will be presented on its body *b*, in the lefthand rotary head 61, the 5 previously described operations occurring respecting the other receivers and bodies. Thereupon valve 78 will again operate to admit pressure to both heads 61, causing rollers 59 of both said heads to operate upon the respective can head seams simultaneously, said rollers of the rotary head at the right in Fig. 1 finishing the seam of the corresponding can head and rollers 59 of head 61 at the left performing the partial seaming of the corresponding can head, both of the master forms 66 of said rotary heads being moved outwardly as before described. When the seams of said can heads have been properly operated on by the respective 10 rollers 59 the pressure is relieved from the corresponding cylinders by the operation of valve 78, rod 88 operates to move both master forms 66 to the left, (Fig. 15), separating the rollers 59 from the can heads, and thereupon plate 94 again operates to withdraw all the receivers and the can bodies from their respective projected positions. Upon the next step of turret A the 15 fully seamed first named can body will be brought to the position *x* opposite a receiver 7^a of turret B. It will be understood that each time plate 94 is rocked to and fro, one of the receivers will receive a can body from track 156, and the other receivers (except at the position *y*), will cause the can bodies thereon to be projected outwardly for the operations described and withdrawn so that, in effect, operations with respect to six can bodies are taking place simultaneously, 20 viz: the application of one can body to a receiver, the pressing of a can body against abutment 30, the application of a head *a* to a can body *b*, the rolling of the seams or flanges of two heads *a*, and the location 25 of a body having a seamed head and projection of said body toward turret B, with the result that one body having a head seamed thereon is ready for delivery at each step of turret A when the corresponding receiver 7 is projected outwardly. Turret B is so timed with relation to turret A that when a body having a seamed can head is projected outwardly at the point *x* the opposing receiver 7^a of turret B will also be 30 projected, whereupon its fingers 108 will grasp the headed end of said can body and thereupon, when plates 94 and 94^e are next operated, the opposing receivers 7 and 7^a will spread apart to release the can body 35 from receiver 7 and leave it upon receiver 7^a. Such operations occur each time the turrets come to rest after turret A has been supplied with a set of can bodies. After a headed and seamed can body is received 40 upon a receiver 7^a turret B will be given an idle step (in the example illustrated) and another receiver 7^a will be brought to position to receive a headed and seamed body from receiver 7, and on the next step of turret B another receiver 7^a will be brought to 45 position to receive a body from a receiver 7 and the first named body *b* on turret B will be brought to position with respect to the beading devices. When plate 94^e is next rocked appropriately the last named body 50 *b* will be projected between dies 119 and 130, and thereupon rod 122 will be moved to cause said dies to squeeze the material at the outer end of body *b*, for beading the same, in manner described before, rod 122 55 thereupon moving back to cause said dies to release the beaded body. Thereupon, upon the next appropriate movement of plate 94^e the corresponding receiver 7^a with the beaded body will be withdrawn from 60 said dies, and on the next step of turret B said beaded body will be brought to an idle position. Upon the next step of turret B said beaded body will be brought opposite the seam bumping or pressing dies 135, 136, 65 90 and upon the appropriate operation of plate 94^e said beaded body will be projected between said dies and the latter will operate to "bump" or press the seam of the body (Fig. 9). Thereupon said dies will separate, and 70 upon the next appropriate movement of plate 94^e the corresponding receiver 7^a with the beaded and bumped can body will be withdrawn from said dies, and on the next step of turret B said body will be brought to an 75 idle position. On the next step of turret B the last named body *b* will be brought to position *z* in Fig. 1, and thereupon, when plate 94^e is moved appropriately, the receiver 80 carrying said body will be moved outwardly 100 and its arm 112 will engage the stop 151 to cause spreading of fingers 108 and release of the body to drop upon the conveyer 150. It will be understood that the four operations, with respect to turret B, of receiving 105 a headed and seamed body from turret A, beading said body, bumping its seam, and delivering such body, will occur in proper order with respect to the various bodies carried by turret B (there being an equal number of receivers on each turret), while operations previously described with respect to 110 turret A are being carried out, the timing of said turrets with respect to one another and the to and fro movement of their corresponding plates 94 and 94^e being so correlated and coincident that for each body *b* received by turret A from track 156 a finished body will be delivered from turret B in the proper sequence or order. 115

While in the machine set forth herein I have illustrated the turrets provided with eight receivers each, and have made provision for six operations with respect to can bodies, including receiving and deliver- 120 125 130

ing them with respect to turret A, and four operations for the can bodies, including receiving and delivering them with respect to turret B, with appropriate idle positions for 5 can bodies with respect to both the receivers, it will be understood that such number of receivers for each turret and such number of operations, with the appropriate devices therefor, may be varied in accordance with 10 the character of the can body to be headed and seamed. Furthermore, that while one rotary head 61 may be utilized for seaming the flanges of the can body heads, two of such rotary heads 61 are set forth herein, 15 whereby partial seaming of the flanges of the heads may be performed by the devices of each rotary head, and this also has reference to the character of flange and seaming thereof desired. If the can bodies are not 20 to have operations produced thereon after they have been headed and seamed, the turret B and the beading and bumping devices may be omitted, and the can bodies may be removed from receivers 7 in any suitable 25 manner. Likewise, the turret B may be utilized for the beading and seam bumping operations on hollow bodies, without regard to the particular means associated with turret A for applying heads and seaming them 30 on the bodies. It will also be understood that the rotary seaming heads may be utilized for seaming flanges of bodies and heads that are presented thereto by any desired means irrespective of the particular 35 turret A and its devices herein set forth.

A particular advantage of my improved rotary seaming head 61 is that it is adapted for readily seaming the flanges on heads of hollow bodies other than circular, such as 40 oval, rectangular, or other polygonal shape, since the rollers 59 may readily move outwardly and inwardly to follow the contour of the bodies, while the desired fluid pressure is maintained on their respective 45 pistons, since, by the arrangements set forth, the pressure on the pistons will be substantially equalized whether the rollers move inwardly or outwardly, according to the contour of the hollow body, because of the 50 communication of the various cylinders one with another, permitting the fluid under pressure to flow from one to another cylinder as may be caused by the different positions of the pistons. While I have shown 55 four rollers 59 and their corresponding cylinders and pistons carried by rotary head 61, it will be understood that the number of such parts and their relative positions may be varied as desired.

60 The abutment 30 may be dispensed with if desired, particularly when the body forming devices are adapted to deliver the formed and seamed bodies to receivers 7 with the edges of the bodies sufficiently accurately

adjusted as to receive the heads *a* in a desired manner, without requiring the bodies to be straightened with respect to their seams.

While I have herein referred to means for forming hollow bodies and feeding such bodies step by step to the receivers 7, it will be understood that, when desired, such hollow bodies may be made separately from the body heading and seaming means set forth but fed to the same step by step as required 75 along the track or other body-delivering means referred to.

Having now described my invention what I claim is:—

1. The combination of devices for forming and delivering hollow bodies, a receiver for said bodies, means spaced from the delivering devices to straighten the bodies on said receiver, means spaced from the straightening means to apply heads upon 85 said bodies, and means spaced from said head applying means to seam the heads while on said bodies, and means to move the bodies from one position to another.

2. The combination of devices for forming and delivering hollow bodies, a receiver for said bodies, means spaced from the delivering devices to apply heads upon said bodies while on the receiver, means spaced from said head applying means to seam the 95 heads while on said receiver, means to operate said receiver to present the bodies successively to the head applying means and to the seaming means, a second receiver spaced from said seaming means and 100 having means to retain the headed and seamed bodies, means to transfer headed bodies from the first to the second receiver, and means to bead said bodies while on the second receiver.

3. The combination of devices for forming and delivering hollow bodies, a receiver for said bodies, means spaced from the delivering devices to apply heads upon said bodies while on the receiver, means spaced from the head applying means to seam the heads while on said receiver, means to operate said receiver, a second receiver spaced from said seaming means and having means to retain the headed and seamed bodies, means spaced from the seaming means to bead said bodies, and means spaced from the beading means to bump the seam at the bead of said bodies.

4. The combination of devices for forming and delivering hollow bodies, a receiver for said bodies, means spaced from the delivering devices to apply heads upon said bodies while on the receiver, means spaced from said head applying means to seam the heads while on said receiver, means to operate said receiver, a second receiver spaced from said seaming means and having fingers 125 to grasp the headed and seamed bodies,

means spaced from the seaming means to bead said bodies, and means to cause said fingers to release the headed and beaded bodies.

5. The combination of devices for forming and delivering hollow bodies, a receiver for the bodies to support them with their outer ends exposed, means to support and rotate the receiver step by step, means to advance and retract said receiver, to carry the body thereon to and fro, means to apply heads upon said bodies while projected outwardly on the receiver, and means to seam the heads while on said bodies.

10 6. The combination of devices for forming and delivering hollow bodies, a receiver for the bodies, means to support and rotate the receiver step by step, means to advance and retract said receiver, an abutment spaced from said delivery means to straighten bodies on the receivers as the latter are advanced, devices spaced from said abutment for applying heads to said bodies while on the receiver, and seaming devices spaced from said head-applying devices for seaming the heads on the bodies.

15 7. The combination of devices for forming and delivering hollow bodies, a receiver for said bodies, means to apply heads upon said bodies on the receiver, means to move the receiver with the body thereon, a rotary head spaced from said applying means and having devices to bear upon the flanges of the body heads for seaming the heads thereto while rotating therearound, and means to advance the receiver with the body and head thereon to said rotary head and to withdraw the seamed body therefrom.

20 8. The combination of devices for forming and delivering hollow bodies, a receiver for said bodies, means to apply heads upon said bodies on the receiver, means to move the receiver with the body thereon, a rotary head spaced from the applying means and having a roller to bear on the body-head flange, means to support the roller for movement relatively to said flange other than rotary, and means to maintain substantially equal pressure of said roller upon said flange in different positions of the roller with respect to the flange to seam the head to the body, and means to advance the receiver with a body and head thereon to said rotary head and to withdraw the seamed body therefrom.

25 9. The combination of means for delivering hollow bodies, a rotative turret, receivers movably carried by said turret, to support bodies with their outer ends exposed, means to rotate the turret with the receivers step by step, means to advance and retract the receivers, to carry the bodies thereon to and fro, means spaced from said delivery means for applying heads upon the exposed ends of

said bodies while advanced on said receivers, 65 and means spaced from said head applying means to seam the flanges of said heads while on said bodies.

10 10. The combination of means for delivering hollow bodies, a rotative turret, receivers movably carried by said turret, to support bodies with their outer ends exposed, means to rotate the turret with the receivers step by step, means to advance and retract the receivers, to carry the bodies thereon to 75 and fro, an abutment spaced from said delivery means to oppose bodies on said receivers, to straighten the bodies thereon, means spaced from said abutment for applying heads upon the exposed ends of said 80 bodies while advanced on said receivers, and means spaced from said head-applying means to seam the flanges of said heads while on said bodies.

11 11. The combination of a rotative turret, 85 slides carried by the turret, means to guide the slides for radial movement relatively to the turret, receivers carried by the slides, a plate having radial grooves and provided with an annular groove communicating with 90 the radial grooves, blocks slidable in the radial grooves and provided with recesses, heads movable in said recesses and in said annular groove, means operatively connecting said slides with said heads, and means to 95 reciprocate said blocks.

12 12. The combination of a rotative turret, slides carried by the turret, means to guide the slides for radial movement relatively to the turret, receivers carried by the slides, a 100 plate having radial grooves and provided with an annular groove communicating with the radial grooves, blocks slidable in the radial grooves and provided with recesses, heads movable in said recesses and in said 105 annular groove, means operatively connecting said slides with said heads, a cam plate movably supported with relation to said blocks, means operatively connecting the blocks with the cam plate, and means to operate the cam plate.

13 13. The combination of a rotative turret, slides carried by the turret, means to guide the slides for radial movement relatively to the turret, receivers carried by the slides, a 115 plate having radial grooves and provided with an annular groove communicating with the radial grooves, blocks slidable in the radial grooves and provided with recesses, heads movable in said recesses and in said 120 annular groove, means operatively connecting said slides with said heads, a plate having a plurality of cam-like slots the same in number as said blocks, means operatively connecting said blocks with the slots of said 125 plate, and means to reciprocate said plate.

14. The combination of a plate having a plurality of spaced radial grooves, a shaft

rotatably supporting said plate, slides operable in said grooves, the plate having slots communicating with said grooves, pins projecting through said slots from said slides, a 5 second plate concentric with the first named plate and having radial grooves, blocks slideable in said grooves and provided with recesses, the second named plate having an annular groove communicating with the 10 radial grooves thereof, heads connected with the pins of said slides and operable in the grooves of said blocks and in said annular groove, means to cause said blocks to reciprocate in the grooves of the second named 15 plate to move said heads and the slides radially, and means to rotate the first named plate.

15. The combination of a plate having a plurality of spaced radial grooves, a shaft 0 rotatively supporting said plate, slides operable in said grooves, the plate having slots communicating with said grooves, pins projecting through said slots from said slides, a second plate concentric with the first named 5 plate and having radial grooves, blocks slideable in said grooves and provided with recesses, the second named plate having an annular groove communicating with the radial grooves thereof, heads connected with 0 the pins of said slides and operable in the grooves of said blocks and in said annular groove, a plate having cam slots, means operatively connecting said blocks with said cam slots, means to rotate the first named 5 plate, and means to oscillate the cam plate.

16. A seaming mechanism comprising a plurality of rollers to operate on an article to be seamed, means movably supporting said rollers, cylinders, means providing communication between said cylinders, pistons in said cylinders operatively connected with said rollers respectively, means to supply said cylinders with fluid pressure, and means to cause said rollers to be retracted 45 from said article after operating thereon.

17. A seaming mechanism comprising a plurality of rollers to operate on an article to be seamed, means movably supporting said rollers, cylinders, means providing communication between said cylinders, pistons in said cylinders operatively connected with said rollers respectively, means to supply said cylinders with fluid pressure, and means to relieve pressure in said cylinders 55 to permit ready retraction of said rollers from said article.

18. A seaming mechanism comprising a plurality of rollers to operate on an article to be seamed, means movably supporting 60 said rollers, cylinders, means providing communication between said cylinders, pistons in said cylinders operatively connected with said rollers respectively, means to supply said cylinders with fluid pressure, a master form substantially conforming to the shape 65

of said article, means coactive between said rollers, pistons and the master form for moving the former by the latter, and means to operate said master form.

19. A seaming mechanism comprising a 70 head, means rotatively supporting said head, a roller carried by said head to operate on an article to be seamed, said head having means to cause the roller to bear with constantly similar pressure upon said article in 75 different positions of said roller around said article, a non-circular master form within said head substantially conforming to the shape of said article, means coactive between said roller and master form for moving the 80 former by the latter, and means to operate said master form relatively to the roller for applying the latter to or removing it from said article.

20. A seaming mechanism comprising a 85 head, means rotatively supporting said head, a roller carried by said head to operate on an article to be seamed, said head having a cylinder, a piston in said cylinder operatively connected with said roller, a channel 90 in the support for the head, said head having a passage providing communication between said channel and cylinder, and means to control the flow of fluid under pressure in said channel, passage and cylinder. 95

21. A seaming mechanism comprising a head, means rotatively supporting said head, a roller carried by said head to operate on an article to be seamed, said head having a cylinder, a piston in said cylinder operatively connected with said roller, a channel 100 in the support for the head, said head having a passage providing communication between said channel and cylinder, means to control the flow of fluid under pressure in 105 said channel, passage and cylinder, a master form substantially conforming to the shape of said article, means coactive between said roller and master form, said master form being carried by said support, and means to 110 adjust said master form on said support relatively to said roller.

22. A seaming mechanism comprising a rotative head provided with a plurality of spaced cylinders, said head having a channel 115 communicating with all of said cylinders, and having a passage communicating with said channel, means to supply fluid under pressure to said passage and channel in all the positions of said head, a plurality of 120 rollers movably supported by said head to coact with an article to be seamed, pistons in said cylinders operatively connected with the respective rollers, and means to control the pressure in said channel and cylinders. 125

23. A seaming mechanism comprising a rotative head provided with a plurality of spaced cylinders, said head having a channel 130 communicating with all of said cylinders, and having a passage communicating with

- said channel, means to supply fluid under pressure to said passage and channel in all the positions of said head, a plurality of rollers movably supported by 5 said head to coact with an article to be seamed, pistons in said cylinders operatively connected with the respective rollers, and means to control the pressure in said channel and cylinders, a master form substantially 10 conforming to the shape of the article to be seamed and coactive with said rollers and pistons, and means to move said master form relatively to said rollers to vary their position with respect to said article.
- 15 24. A seaming mechanism comprising a mandrel having a die to coact with an article to be seamed, a head rotatively supported upon said mandrel and provided with a plurality of spaced cylinders, pistons in 20 said cylinders, rollers spaced apart around said die and movably carried by said head, means connecting said rollers with said pistons, said head having an annular channel communicating with said cylinders and having a passage communicating with said channel, a chamber between the mandrel and head communicating with said passage, a channel communicating with said chamber, and means to control admission of fluid 25 under pressure to said channel.
- 25 26. A seaming mechanism comprising a mandrel having a die to coact with an article to be seamed, a head rotatively supported upon said mandrel and provided with 30 a plurality of spaced cylinders, pistons in said cylinders, rollers spaced apart around said die and movably carried by said head, means connecting said rollers with said pistons, said head having an annular channel 35 communicating with said cylinders and having a passage communicating with said channel, a chamber between the mandrel and head communicating with said passage, a channel communicating with said chamber, and means to control admission of fluid 40 under pressure to said channel, a master movable relatively to said die and coactive with said rollers and pistons, and means to move said master relatively to said die and 45 rollers.
- 50 26. A seaming mechanism comprising a mandrel having a die to coact with an article to be seamed, a head rotatively supported upon said mandrel and provided with 55 a plurality of spaced cylinders, pistons in said cylinders, rollers spaced apart around said die and movably carried by said head, means connecting said rollers with said pistons, said head having an annular channel 60 communicating with said cylinders and having a passage communicating with said channel, a chamber between the mandrel and head communicating with said passage, a channel communicating with said chamber, and means to control admission of fluid 65 under pressure to said channel.
- under pressure to said channel, a master 70 slideable upon said mandrel and coactive with said rollers and pistons, rods slideable in the mandrel and connected with the master, and means to move said rods to adjust the mandrel relatively to the rollers.
27. A seaming mechanism comprising a head provided with a plurality of cylinders open at opposite ends through the head, a shell surrounding the head providing a 75 channel communicating with said cylinders, means to movably retain the shell in place, pistons in said cylinders, rollers connected with said pistons, said head having a passage communicating with said channel, and 80 means to control the supply of fluid under pressure to said channel and cylinders.
28. A seaming mechanism comprising a head provided with a plurality of cylinders and having a channel communicating with 85 said cylinders, a mandrel, said head having a hub rotative on said mandrel providing a chamber therebetween, packing at opposite sides of said chamber surrounding said mandrel and within said hub, said mandrel 90 having a channel communicating with said chamber, said head having a passage communicating with said chamber and with the first named channel, pistons in said cylinders, and rollers to coact with an article to 95 be seamed and operatively connected with said pistons.
29. The combination of a rotative turret, receivers for hollow bodies carried by said 100 turret, inner dies spaced from said turret to enter said bodies, means movably supporting said dies for separation, outer dies spaced apart around the inner dies to receive said bodies therebetween, a rod movable relatively to said dies, a mandrel operative 105 by said rod and slideable within the inner dies for expanding them, said rod being provided with cam-like projections to coact with the outer dies, whereby when the rod is reciprocated said dies will be caused to 110 bead hollow bodies and release the same, and means to operate said rod.
30. The combination of a rotative turret, receivers carried by the turret and adapted 115 to support hollow bodies, beading dies for said bodies, located adjacent to the turret, means to cause operation of said dies, means to cause the receivers to present said bodies between and remove them from said dies, seam bumping dies spaced from said beading dies and said turret and spaced apart to receive the beaded seams of said bodies therebetween, means to cause said dies to bump said beaded seams and means to release said bodies.
31. The combination of a rotative turret, receivers carried by the turret, fingers carried by said receivers to retain hollow bodies thereon, means to advance and retract said receivers respecting said turret, beading dies 120 125 130

for said bodies, located adjacent to the turret, means to cause operation of said dies, a stop spaced from the beading dies, one of the fingers of each receiver having means 5 to coact with said stop for causing release of can bodies during reciprocation of the corresponding receiver.

32. The combination of a rotative turret, receivers carried by the turret, fingers carried by said receivers to retain hollow bodies thereon, means to advance and retract said receivers respecting said turret, beading dies for said bodies, located adjacent to the turret, means to cause operation of said 10 dies, a stop spaced from the beading dies, one of the fingers of each receiver having means to coact with said stop for causing release of can bodies during reciprocation of the corresponding receiver, plungers carried 15 by said receivers, and means coöperative between the corresponding fingers and plungers for causing projection of the plungers when the fingers are spread apart and retraction of the plungers when the fingers approach.

33. The combination of a rotative turret, receivers carried by the turret, opposing fingers pivotally carried by each receiver to receive hollow bodies therebetween, springs 20 normally causing said fingers to approach, means operatively connecting the fingers of each receiver, an arm connected with a finger of each receiver, means to advance and retract said receivers respecting said turret, beading dies for said bodies, located adjacent to the turret, means to cause operation of 25 said dies, and a stop spaced from the beading dies in position to coact with said arms to cause spreading of the corresponding 30 fingers of a receiver upon advancing of the corresponding receiver.

34. The combination of a rotative turret having a plurality of radially disposed receivers adapted to enter hollow bodies, 25 means upon said receivers to retain said bodies thereon, means to cause said turret to rotate step by step, means to advance and retract some of the receivers at the termination of each step of the turret, means to apply heads 30 upon said bodies while on said receivers, means to seam the heads on said bodies while on said receivers, a second turret spaced from the first named turret, receivers carried by the second named turret, 35 means to rotate said turret step by step, means to advance and retract the receivers of said turret, the rotating means for said turrets being adapted to cause said turrets to stop with corresponding receivers opposed and spaced apart, the advancing and retracting means for the receivers of said turrets being connected together for causing the opposing receivers of the turrets to be advanced toward and retracted from each other, the receivers of the second named turret having means to grasp the headed ends of the hollow bodies and withdraw them from the receivers of the first named turret, means spaced from the second named turret to bead the unheaded end portions of said hollow bodies, and means to cause release of headed and beaded bodies from the last named receivers.

to stop with corresponding receivers opposed and spaced apart, the advancing and retracting means for the receivers of said turrets being connected together for causing the opposing receivers of the turrets to be advanced toward and retracted from each other, the receivers of the second named turret having means to grasp the headed ends of the hollow bodies and withdraw them from the receivers of the first named turret, means spaced from the second named turret to bead the unheaded end portions of said hollow bodies, and means to cause release of headed and beaded bodies from the last named receivers.

35. The combination of a rotative turret having a plurality of radially disposed receivers adapted to enter hollow bodies, means upon said receivers to retain said bodies thereon, means to cause said turret to rotate step by step, means to advance and retract the receivers at the termination of each step of the turret, means to apply heads upon said bodies while on said receivers, means to seam the heads on said bodies while on said receivers, a second turret spaced from the first named turret, receivers carried by the second named turret, means to rotate said turret step by step, means to advance and retract the receivers of said turret, the rotating means for said turrets being adapted to cause said turrets to stop with corresponding receivers opposed and spaced apart, the advancing and retracting means for the receivers of said turrets being connected together for causing the opposing receivers of the turrets to be advanced toward and retracted from each other, the receivers of the second named turret having means to grasp the headed ends of the hollow bodies and withdraw them from the receivers of the first named turret, means spaced from the second named turret to bead the unheaded end portions of said hollow bodies, seam bumping dies spaced from the turret and from the beading dies to receive the beaded seam of said bodies therebetween to bump and release said seams, and means to cause release of headed, beaded and bumped bodies from the last named receivers.

Signed at New York city, in the county of New York, and State of New York, this 27th day of April, A. D. 1916.

ERNEST D. ANDERSON.
